UNITED STATES PATENT OFFICE.

JULIUS H. SCHLAFLY, OF CANTON, OHIO, ASSIGNOR TO UNITED ALLOY STEEL CORPORATION, OF CANTON, OHIO, A CORPORATION OF NEW YORK.

CULVERT.

Application filed January 3, 1924. Serial No. 684,138.

- The invention relates to improvements in sheet metal culverts of the sectional, nestable, or knock-down type. Such culverts are commonly formed of half round sections, 5 corrugated transversely, and terminating at their sides in connecting flanges provided with corrugations conforming to the arch corrugation of the body portion of the section.
- 10 In assembling culverts of this type, when it is desired to form a square end, differential sections must be employed, one of which terminates in a flared end and the other of which terminates in a contracted end. Such 15 a construction is illustrated in my prior Patent No. 882,081 of March 17, 1908, and requires the manufacturer to make differential sections which makes it necessary for the dealer to keep the same in stock.
- 20 This not only increases the cost of manufacturing but requires considerable care in filling an order to insure that the proper kind of sections are included, in order to terminate a culvert with a square end without 25 an excessive amount of overlapping sections at the end joints.

The object of the present invention is to provide a corrugated sectional culvert which will overcome these difficulties, and is attained by forming the culvert of interchangeable sections wherein the flange on one side is provided with corrugations which are concaved in conformity with the arch corrugations while the flange on the other 35 side is provided with corrugations which are concaved reversely with respect to the arch corrugations, whereby when one section is laid upon the other, in assembling the culvert, the flange corrugations will register 40 and nest one within the other, while the ends of the sections are alike.

The invention is illustrated in the accompanying drawings, being part hereof, in which—

45 Figure 1 is a plan view of a culvert section embodying the invention;

Fig. 2, a side elevation of two section assembled;

50 Fig. 3, an enlarged section on the line 3—3, Fig. 2;

Fig. 4, a fragmentary perspective view of portions of two sections showing the same in position to be assembled;

55 Fig. 5, a side elevation of a portion of a culvert embodying the invention; and

Fig. 6, an end elevation of several of the culvert sections nested.

Similar numerals of reference refer to corresponding parts throughout the drawings.

The culvert sections indicated at 1 are 60 each of the same kind or type and may be of any suitable length. Each section is semi-cylindrical and is preferably corrugated transversely with the arch corrugations 2, and it is essential that each end of 65 the section be alike, the sections preferably terminating in the flared ends 3 as illustrated.

Each section is provided along its side edges with the angular attaching flanges 4 70 and 5, the flange 4 being provided with corrugations 6, conforming to the arch corrugations 2, in the body portion of the section, while the flange 5 is provided with corrugations 7 concaved reversely with respect to 75 the arch corrugations.

Thus, when two sections are assembled, as shown in Fig. 2, the corrugated attaching flanges will register and nest, and a square end will be provided at each end of the culvert. Bolts 8 or other suitable fastening 80 means may be provided for connecting the flanges together.

As shown in Fig. 5, when it is desired to stagger the joints throughout the length of 85 the culvert, the same may be built up of full length sections 1, and half length sections 1^a, formed as above described, only a single type of section being required.

Sections of this type may be easily nested 90 together as shown in Fig. 3, as the corrugated flanges 4 upon the one side and the corrugated flanges 5 upon the other side of each section register and nest together in the same manner as the arch corrugations 2 95 through the body portions of the sections.

By the described construction and arrangement of the improved form of culvert sections it is only necessary for the manufacturer to make, and the dealer to keep in 100 stock, one type or kind of sections, thus reducing the manufacturing cost and obviating the possibility of including the wrong type of sections in filling an order; making it possible to terminate a built up culvert with square ends, without the necessity of using differential sections and without an excessive amount of overlapping of sections at the end joints of the culvert.

If desired, the culvert may be made up of 110

sections all of one length, placed together in the manner shown in Fig. 2, the ends of adjacent pairs of sections being lapped and bolted together.

5. I claim:

1. A culvert section having lateral flanges with transverse corrugations reversely formed on opposite side edges.

10 2. A culvert section provided with transversely corrugated flanges at its side edges, the corrugations in one flange being formed reversely with respect to the corrugations in the other flange.

15 3. A corrugated culvert section terminated alike at both ends and having transversely corrugated flanges at its side edges, the corrugations on one flange being formed reversely with respect to the corrugations upon the other flange.

20 4. A corrugated culvert section having corrugated flanges at its side edges, the corrugations in one flange being formed the same as the corrugations in the body of the

section, and the corrugations in the other flange being formed reversely with respect thereto.

5. A corrugated culvert section terminated alike at both ends and having corrugated flanges at its side edges, the corrugations in one flange being formed the same as the corrugations in the body of the section and the corrugations in the other flange being formed reversely to the corrugations in the body of the section.

6. A culvert composed of corrugated sections, all of which are alike, each section terminating in flared ends and having transversely corrugated flanges at its side edges, the corrugations upon each flange being formed reversely with respect to the corrugations in the other flange.

7. A culvert composed of sections, all of which are alike, each section having transversely and reversely corrugated flanges upon opposite side edges.

JULIUS H. SCHLAFLY.
